UNITED STATES PATENT OFFICE.

FREDERICK H. STONEBURN, OF MANSFIELD, CONNECTICUT, ASSIGNOR TO
THE CORNELL INCUBATOR MFG. CO., OF ITHACA, NEW YORK.

INCUBATOR.

SPECIFICATION forming part of Letters Patent No. 729,695, dated June 2, 1903.

Application filed February 5, 1903. Serial No. 141,968. (No model.)

To all whom it may concern:

Be it known that I, FREDERICK H. STONEBURN, a citizen of the United States, residing at Mansfield, in the county of Tolland and State of Connecticut, have invented certain new and useful Improvements in Incubators, of which the following is a specification.

My invention relates to improvements in incubators in which a thermostat is used with regulating connection between thermostat and heater.

The objects of my invention are, first, to provide an incubator with no rods or other regulating devices projecting through or above its top; second, to house and inclose such devices so that they will not be accidentally or negligently disturbed or interfered with; third, to secure and maintain at the same time in the incubator and its regulation greater efficiency and security. I attain these objects by the mechanism and construction illustrated in the accompanying drawings, in which—

Figure 1 is a perspective view of an incubator. Fig. 2 is a top view with the outer top casing removed. Fig. 3 is a vertical section of a part of the incubator on the line A B in Figs. 1 and 2. Fig. 4 is a detailed view in perspective of the principal features of my invention.

Similar figures refer to similar parts throughout the several views.

In Fig. 3 the incubator-chamber 1 is shown with thermostat 2, connecting-rod 3 extending upward through the inner wall 9 to connection with the lever-arm 4 in the walled-off chamber or pocket 6. This pocket 6 is walled off within the air-space 7 between the outer or top casing 8 and the inner wall or casing 9 and is preferably built so that the air-space 7 is continuous between the bottom of the pocket 6 and the wall 9. When the top casing 8 is in position, the pocket 6 is without any communication with the chamber 1 or the air-space 7 except through the small hole 10, through which the connecting-rod 3 passes, and this, with such rod in position, will be approximately air-tight. The lever-arm 4 is pivoted, as at 11, in any appropriate manner with adjustable counterweight 12 and adjusting-nuts 13 14 on the rod 3. The

other end of the arm 4 projects through the side 15 of the incubator, through the slot 16, to connection with damper or other heat-regulator 17 of the heater 18. Through the top 55 casing 8, over the connecting-rod 3, a door or handhole 19 is made, giving access to the pocket 6 for purposes of adjustment, but which is normally closed by the flush door or lid 20.

Heretofore the top of the incubator is usually encumbered with the projection above it of the connecting-rod and lever-arm, which are frequently interfered with by curious or thoughtless persons by putting hats or coats 65 on them or otherwise, and thereby destroying the automatic regulation of the temperature of the incubator-chamber, to the serious injury or entire loss of the hatch. Such danger of interference is practically eliminated 70 by my invention, and I at the same time secure a flat table-top for the incubator, upon which any article may be placed with no interference with the operation of the incubator.

Having thus described my invention, what I claim, and desire to secure by Letters Patent, is—

1. In an incubator a walled-off pocket or chamber separate from the egg-chamber, but 80 within the body of the incubator, a thermostat in the egg-chamber, a pivoted lever-arm in the pocket and adjustably connected at one end with the thermostat and at the other with the damper or other heat-regulator of 85 the heater.

2. In an incubator a walled-off pocket or chamber separate from the egg-chamber, and within the body of the incubator, a thermostat in the egg-chamber, a pivoted lever-arm 90 in the pocket and adjustably connected at one end with the thermostat and at the other with the damper or other heat-regulator of the heater, and means of access to said pocket through the top or outer wall of the incubator, 95 for the purpose specified.

In testimony whereof I affix my signature in presence of two witnesses.

FREDERICK H. STONEBURN.
